STROKE CONTROL FOR FREE-PISTON UNITS

Andrew Kalitinsky, Eagleville, Conn., assignor to
United Aircraft Corporation, East Hartford,
Conn., a corporation of Delaware

Application July 23, 1943, Serial No. 495,918

2 Claims. (Cl. 230—56)

1

This invention relates to a free-piston engine-and-compressor unit adapted for compressing gaseous media of various densities.

In a conventional free-piston engine-and-compressor unit, the compressor, when designed for compressing one density of medium, is improperly dimensioned for compressing other densities. An object of the invention is to overcome the above difficulty so that the unit will operate properly regardless of density.

Free-piston engines are usually of the two-cycle type and exhaust ports which are near the ends of the engine cylinder must be fully uncovered by the pistons for proper engine operation. A variation in the density of the medium pumped by the compressor affects the length and position of the piston stroke and may cause incomplete uncovering of the ports. One feature of the invention is the avoiding of this difficulty by controlling the flow of the medium through the compressor cylinders.

When these units are used in aircraft, if they are designed for one ambient pressure, i. e. altitude, they are not properly designed for other altitudes. Another feature of the invention is the control of a free-piston unit so that its operation may be independent of altitude changes.

Other objects and advantages will be apparent from the specification and claims, and from the accompanying drawings which illustrate an embodiment of the invention.

Fig. 1 is a sectional view through the free-piston engine-and-compressor unit.

Fig. 2 is a fragmentary section taken on line 2—2 of Fig. 1.

The unit shown includes an engine cylinder 10 having reciprocating pistons 12 and 14 to which compressor pistons 16 and 18 in cylinders 20 and 22 are integrally connected. Sleeves 24 and 26 attached to the compressor pistons complete the reciprocating piston assemblies. The sleeves in combination with stationary pistons 28 and 30 form air spring cylinders.

The piston assemblies are moved apart by the burning of fuel injected into engine cylinder 10. Air compressed in the air spring cylinders on the power stroke returns the piston assemblies. The assemblies are maintained at equal distances from the center of the engine cylinder by a linkage which may include racks 34 extending from the compressor pistons and engaging opposite sides of a pinion, not shown.

Intake manifold 38 conducts air to intake valves 40 through which air alternately enters opposite ends of the compressor cylinders. The com-

2

pressed air leaves the cylinders through discharge valves 42, also at opposite ends of the compressor cylinders, and passes through scavenging manifold 44 through ports 46 and 48 which are uncovered by pistons 12 and 14 at the end of the power stroke, thereby permitting air to be blown through the engine cylinder and exhaust ports 50 and 52 into exhaust manifold 54.

The engine-and-compressor unit operates to best advantage provided the density of the medium being pumped by the compressor remains uniform. A change in the density of the medium being pumped shortens or lengthens the piston stroke so that, either the engine ports are not fully uncovered or, in the case of an excessively long stroke, the pistons may strike each other or the ends of the cylinders. When the unit is used in aircraft, the change in the density of the medium between sea level and cruising altitude is enough so that adjustments are necessary for efficient operation of the unit. In this invention the length of the piston stroke is adjusted by controlling the flow of the medium through the compressor cylinders.

If the density increases substantially above that for which the unit is designed, the strokes of the pistons shorten to such an extent that the scavenging and exhaust ports of the engine cylinder are not fully uncovered during the piston movement. To adjust for this increase in density, interconnected valves 56 and 56' are provided in the passages 58 leading from intake manifold 38 to the chamber 60 which communicates with intake valves 40 at the inner ends of the compressor cylinders. In effect, throttling by closing valves 56 and 56' tends to convert the unit into a single-acting compressor with the work of compressing being done in the outer ends of the compressor cylinders.

Since substantially all the energy developed in the engine cylinder must be absorbed during the outer stroke of the pistons, the stroke will be lengthened and the engine ports will be fully uncovered. The unit is thus adapted to compress a medium of greater density, without affecting the operation of the unit, by closing valves 56. These may be operated by a rod 62 on which valves 56 are mounted and a parallel rod 62' on which valves 56' are mounted. A linkage 63 connects the rods 62 and 62' so that they move simultaneously when rod 62 is turned. Rod 62 may have an arm 64 by which the valves may be manually controlled.

It is to be understood that the invention is not limited to the specific embodiment herein illus-

trated and described, but may be used in other ways without departure from its spirit as defined by the following claims.

I claim:

1. A free-piston engine-and-compressor unit including an engine cylinder having scavange and exhaust ports, a compressor cylinder having intake and discharge valves at each end, free pistons in said cylinders and reciprocating as a unit, said pistons having a variable length of stroke with the piston in the engine cylinder adapted to cover and uncover said ports, a supporting structure interconnecting said engine and compressor cylinders and forming a passage for the admission of gas to the end of the compressor cylinder adjacent to the engine cylinder, in combination with means for throttling the admission of gas to the end of the compressor cylinder adjacent to the engine cylinder. 15

2. A double acting free-piston engine-and-compressor unit including an engine cylinder having scavange and exhaust ports, a compressor cylinder adjacent each end of the engine cylinder, each compressor cylinder having intake and discharge valves at each end, a supporting structure interconnecting the compressor and engine cylinders and forming passages therein communicating with the inlet valves at the inner ends of the compressor, engine pistons in said engine cylinder and compressor pistons in the compressor cylin- 20 25 30

ders, each compressor piston being connected to and moving with the adjacent engine piston, each engine piston having a variable length stroke and being adapted to cover and uncover the ports and means for limiting the admission of gas to the inner ends of the compressor cylinders including throttles located in the passages to the inner ends of the cylinders and means for moving all of the throttles simultaneously.
